United States Patent Office

Des. 229,250

Patented Nov. 20, 1973

229,250

FRENCH FRIED POTATO PRODUCT

James E. Citti, Mound, and Carl S. Dienst, Edina, Minn.,
assignors to Ore-Ida Foods, Inc., Ontario, Oreg.

Filed Mar. 26, 1971, Ser. No. 128,638

Term of patent 14 years

Int. Cl. D1—01

U.S. Cl. D1—21

FIG. 1

FIG. 2

FIG. 3

FIG. 4

FIG. 1 is a side elevational view of a French fried potato product showing the new design;

FIG. 2 is a similar view thereof, but taken after the French fried potato product has been rotated 45° from its position in FIG. 1;

FIG. 3 is an end elevational view looking from the left in FIG. 1; and

FIG. 4 is a view similar to that of FIG. 3 but looking toward the right end of FIG. 1.

We claim:

The ornamental design for a French fried potato product, substantially as shown.
